UNITED STATES PATENT OFFICE.

EARL H. HOWARD, OF LOS ANGELES, CALIFORNIA, ASSIGNOR TO GILFILLAN BROS.
SMEILING & REFINING COMPANY, OF LOS ANGELES, CALIFORNIA, A CORPORATION OF CALIFORNIA.

VALVE GRINDER.

Application filed August 8, 1919. Serial No. 316,049.

To all whom it may concern:

Be it known that I, EARL H. HOWARD, a citizen of the United States, residing at Los Angeles, in the county of Los Angeles, State 5 of California, have invented new and useful Improvements in Valve Grinders, of which the following is a specification.

This invention relates to valve grinding machines and particularly to valve grinding machines adapted to be used for grinding in poppet valves such as are used in internal combustion engines common in automobile practice. It is an object of the invention to provide a simple, compact and effective 15 machine of this character.

In order that poppet valves be tight they must be made to seat properly. Valves of this type are generally made to seat tightly and properly by grinding them in with emery. This grinding in is generally done by placing a compound of emery between the valve and the valve seat and then giving the valve an oscillating rotating motion by means of a screw-driver or the like. The 20 reason for giving the valve an oscillating, rotating motion—that is, a motion so that it rotates through a small angle in one direction and then rotates through a small angle in the other direction, is because continuous rotation of the valve in one direction will cause rings or grooves to form either in the valve seat or in the valve itself. The 25 grinding in of valves by hand is slow and laborious and is therefore expensive. By 30 the present invention an electrically driven machine is provided which will properly grind in a valve in a fraction of the time required to do it by hand.

The present invention provides a machine 40 in which an electric motor, through a suitable mechanism, gives an oscillating, rotative motion, such as is required for grinding in a valve, to a shaft. This shaft which is driven by the motor is adapted to have a 45 member attached to it which will engage a valve so as to cause it to be driven by said shaft.

A particular feature of the invention is the compactness and simplicity of the mechanism which gives the required motion to the shaft. The compactness of the mechanism makes the machine easy to handle while the simplicity minimizes the danger of parts

getting out of order and thereby makes the machine particularly durable.

Further objects and features of the invention will be readily understood from the following detailed description of a preferred form of the invention in which reference is had to the accompanying drawings in 55 which—

Fig. 1 is a side elevation of the machine; Fig. 2 is an enlarged detail section taken as indicated by lines 2—2 on Fig. 1; Fig. 3 is a detail section taken as indicated by line 65 3—3 on Fig. 2; Fig. 4 is a detail section taken as indicated by line 4—4 on Fig. 3; Fig. 5 is a detail section taken as indicated by line 5—5 on Fig. 2; and Fig. 6 is a detail section taken as indicated by line 6—6 on 70 Fig. 5.

Throughout the drawings numeral 10 designates the casing of the machine in which is carried an electric motor. The casing 10 is preferably shaped as shown in Fig. 1 so as 75 to form a handle 11 which provides a convenient means for handling the machine. A portion 12 of the casing in which there is a switch is preferably provided near the handle 11, and a button 13 for operating 80 the switch in portion 12 may be located so that it may be conveniently operated from the handle 11. Lead wires 14 enter the machine through a conductor 15 and the current entering the machine through lead wires 14 85 is controlled by the switch in the portion 12. Suitable ventilating holes 16 and 17 may be provided in the casing 10 to allow a circulation of air around the motor within said casing to prevent it from becoming over- 90 heated. The shape, arrangement and proportions of the casing 10 may be varied to suit conditions but it is preferred that they be substantially as shown in the drawings.

The shaft 18, of the motor which is within 95 the casing 10, extends from the bottom 19 of said casing 10, and has mounted on it a pinion 20. The pinion 20 engages and drives a gear 21 which is mounted on a pivot pin 22. The pivot pin 22 is mounted in and 100 extends from the bottom 19 of the casing 10. Formed integral with the gear 21 and therefore driven by said gear there is a pinion 23 arranged as shown in Fig. 3. The pinion 23 engages and drives a large gear 24 which 105 is mounted on a pivot pin 25. The pivot

pin 25 is mounted in and extends from the bottom 19 in the same manner as pivot pin 22 and the gear 24 is provided with a boss 26 which separates said gear from the bottom 19 so that it is in line with pinion 23 as shown in Fig. 3. It will be noted that the pinion 20 and the gear 21 are close against the bottom 19 and that the pinion 23 and the gear 24 are only a short distance from the pinion 20 in gear 21. This arrangement provides a simple and compact mechanism in which sufficient speed reduction is obtained between the motor shaft 18 and the gear 24 to allow a high speed motor to be used in order to drive the gear 24 at a suitable speed.

A substantially square bar 28 is eccentrically mounted on the gear 24 at 29 by means of a pin 50. The bar 28 being eccentrically pivoted on the gear 24 and carried in a guide, as will hereinafter be described, is given a reciprocating motion in said guide when gear 24 is rotated. On one side of the bar 28 there are gear teeth 25 which form a rack 30. The rack 30 engages a spur gear 31 which is mounted on a shaft 32. The shaft 32 is carried in a bearing 33 in the housing or cover 34. The cover 34 is preferably a casting which is adapted to fit over the entire mechanism just described and thereby encase it. The cover 34 may be attached to the casing 10 by means of screws 35. Pivotaly mounted on the shaft 32 between the portion 36 of the cover 34 and the gear 31 there is an arm 37. The arm 37 extends over the bar 28 and has a projection 38 at its end which engages side 39 of the bar 28. It will be particularly noted that the projection 38 is curved or shaped so that only the ends 38^a engage the side 39 of the bar 28. This construction has been found in practice to be very satisfactory as it completely eliminates binding of the bar 28 between the projection 38 and the gear 31. It will be readily seen how the projection 38 causes the bar 28 to be held in the proper position relative to the gear 31 at all times. When the gear 24 is rotated the bar 28 will be caused to reciprocate between the portion 38 of the arm 37 and the gear 31, which reciprocation, due to the rack 30 engaging the gear 31, will cause gear 31 to rotate a portion of a revolution in one direction and then rotate a portion of the revolution in the other direction. It will be readily understood that the amount of rotation in one direction of the gear 31 is dependent upon the eccentricity of the pin 50 and the size of gear 31. By varying the amount of eccentricity of pin 50 and the size of gear 31, the gear may be made to rotate through any desired angle.

The shaft 32 may be made to extend any

desired distance beyond the bearing 33 and its end 40 may be adapted to have any particular form or kind of tool mounted on or connected to it. It is preferred, however, that a simple means be provided for mounting a shank 41 on the end 40, said shank being provided with a flattened or substantially screw-driver shaped end 42. The end 42 is preferably made so that it will engage the slot 43 which is generally provided in poppet valves such as are used in automobile practice.

In the preferred form of the invention the mechanism is so arranged as to cause an electric motor adapted to run at about 8000 revolutions per minute to drive the shaft 32 at the rate of about 600 oscillations per minute and to cause said shaft to rotate through approximately 90°.

With a machine of these general proportions, a valve of ordinary size and under ordinary condition can be ground in a very few minutes. When a valve is being ground it is preferred that the entire machine be moved or rotated slightly by the handle 11 to prevent the valve from rotating back and forth in the same place. Although a valve may be satisfactorily ground in without rotation of the machine, it is preferred to rotate it for best results.

Having described a preferred form of the invention, I do not wish to limit myself to the details hereinabove set forth but wish to reserve to myself any changes or modification that may fall within the scope of the following claim.

Having described a preferred form of my invention, I claim:

In combination, an electric motor including a casing and a shaft extending from one end of the casing, a housing attached to said end of the casing, a pinion on the shaft in the housing, a gear mounted in the housing to mesh with the pinion, a second pinion formed with said gear, a second gear mounted in the housing to mesh with said second pinion and to overlie the first mentioned gear, a spindle having one end projecting into the housing and having one end extending from the housing, a gear mounted on the spindle in the housing, a rack bar pivotally connected to said second gear to be operated thereby and meshing with the gear mounted on the spindle, and a guide member pivotally carried by the spindle and engaging the rack bar to hold it in mesh with the gear on the spindle.

In witness that I claim the foregoing I have hereunto subscribed my name this 23d day of July 1919.

EARL H. HOWARD.

Witness:

VIRGINIA BERNINGER.
